UNITED STATES PATENT OFFICE.

ABRAHAM ROLAND, OF WESTOVER'S, ASSIGNOR OF ONE-HALF TO JAMES M. BUNN, OF NEW WASHINGTON, PENNSYLVANIA.

WRENCH.

SPECIFICATION forming part of Letters Patent No. 379,984, dated March 27, 1888.

Application filed April 6, 1887. Serial No. 233,913. (No model.)

To all whom it may concern:

Be it known that I, ABRAHAM ROLAND, a citizen of the United States of America, residing at Westover's, in the county of Clearfield 5 and State of Pennsylvania, have invented certain new and useful Improvements in Ratchet-Wrenches, of which the following is a specification, reference being had therein to the accompanying drawings.

10 My invention relates to improvements in wrenches; and its objects are, first, to provide a wrench affording a perfect leverage; second, to permit of the ready duplication or renewal of the parts; third, to obviate the necessity of withdrawing and replacing the wrench over the nut at each quarter or half revolution; fourth, to provide a rigid wrench whose opposite faces will engage nuts of variant diameters; fifth, to maintain continuously a stable and effective correlation of the parts; and, sixth, to accomplish these ends with structural simplicity and economy. I attain these purposes by the device shown on the accompanying drawings, in which—

25 Figure 1 represents a longitudinal sectional elevation of my invention. Fig. 2 is a plan view of the same, partly in section. Fig. 3 is a detail elevation of a sliding block whereby the parts can be disjoined; and Fig. 4 is a plan view of the same block, illustrating its lower inner face.

The same designations indicate corresponding parts.

To a suitable handle, A, is secured a bifurcated frame, D, within which the pawls B B' are pivotally secured by pins C C'. The pawls are maintained in engagement with the cogged wheel F by the springs E E', affixed antipodally to suitable sockets in the base of the frame

40 D. The breaking of contact simultaneously or successively between the pawls B B' and

the wheel F can only therefore be effected by pressing the inner ends of said pawl-levers against the retractile force of the springs. The wheel F has rigidly secured on its upper 45 face a centrally-perforated flange having the countersunk depression H, to fit over a nut. To its lower face a similarly-perforated beveled block is secured by means of a dovetailed connection, so that the corresponding groove, 50 L, in the sliding block K will engage therewith and unite the parts. The outer face of the block K has a similar countersunk depression, H', adapted to fit a nut of different diameter. A catch, I, when screwed up, 55 serves to lock the parts together.

It will be understood that when it is desired to obtain a new hold on the handle A it will simply be necessary to release the pawls B B' from engagement with the cog-wheel F. 60

Having thus fully described my improvements, what I claim, and desire to secure by Letters Patent of the United States, is—

As a new article of manufacture, a wrench consisting of the combination, with a bifurcated frame, D, secured to a handle, A, and provided with the spring-actuated pawls B B', and the cog-wheel F, having the depression H on one face and the perforated beveled block rigidly secured thereto on the other 65 face, of the sliding block K, having a depression, H', a groove, L, and a catch, I, the whole co-operating as and for the purpose set forth. 70

In testimony whereof I affix my signature in presence of two witnesses.

ABRAHAM + ROLAND.
his
mark.
